ATTORNEY.

UNITED STATES PATENT OFFICE.

JOHN M. MARCO, OF PHILADELPHIA, PENNSYLVANIA.

LINGO FOR LOOMS.

SPECIFICATION forming part of Letters Patent No. 461,638, dated October 20, 1891.

Application filed July 16, 1890. Serial No. 358,902. (No model.)

To all whom it may concern:

Be it known that I, JOHN M. MARCO, a citizen of the United States, residing in the city and county of Philadelphia, State of Pennsylvania, have invented a new and useful Improvement in Lingoes or Heddle-Weights for Looms, which improvement is fully set forth in the following specification and accompanying drawings.

- 10 My invention consists of improvements in lingoes or weights, whereby heddles may be kept in proper position and other advantages are obtained, as will be hereinafter fully set forth.
- 15 Figure 1 represents a perspective view of a piece of material of which the lingo or heddle-weight embodying my invention is made. Figs. 2, 3, and 4 represent perspective views of a lingo or heddle-weight embodying my invention. Fig. 5 represents a section of a portion of a heddle-weight on line xx , Fig. 4.

Similar letters of reference indicate corresponding parts in the several figures.

Referring to the drawings, A designates a lingo or heddle-weight, and B designates a portion of a heddle attached thereto.

The lingo is formed of a piece of metal or other suitable material bent or doubled upon itself, forming two lengths, which are connected at one end by the neck C and separated the remaining length of the piece. On the inner faces of the pieces are longitudinally-extending grooves D, and on the outside of the connected ends of the two pieces 35 of the lingo, adjacent to the neck of the pieces, are grooves E. It will be seen that the eye of the heddle may be readily connected with the lingo by inserting said eye over either of the pieces constituting the lingo, at the open 40 end thereof, and then running the eye toward the connected end of the two pieces or parts of the same until the eye of the heddle occu-

pies the ends of grooves E at the closed end. Owing to the grooves D, the twisted or other connected end of the eye of the heddle may 45 readily ride through the grooves D until it reaches its place of occupation. The groove or recess also allows the pieces or lengths of the lingo to be closed to full extent without interference of the end of the heddle-eye. 50 Furthermore, the ends of the heddle are prevented from locking together, and they cannot be undone in operation, as is the case with the cord-knot, or unclasped, as with the wire-heddle. Owing to the grooves or recesses E, 55 the eye of the heddle sets snugly and comparatively flush in position and readily retains its position.

In practice I form the lingo or weight of half-round or square-faced wire, the same 60 being bent or doubled and grooved or recessed, as has been stated.

Having thus described my invention, what I claim as new, and desire to secure by Letters Patent, is—

65

1. A lingo formed of a piece of material doubled or bent as described and formed with grooves on the inner adjacent faces, substantially as described.
2. A lingo formed of a piece of material 70 doubled or bent as described and formed with grooves on the inner adjacent faces and grooves on the outside of the connected ends, substantially as described.
3. A lingo formed of doubled material with 75 a groove or recess on the inner faces of the pieces comprising the same, the connecting-neck of the pieces forming means of attachment for the eye of the heddle, substantially as described.

JOHN M. MARCO.
